UNITED STATES PATENT OFFICE.

HOWARD S. McBRIDE, OF NEW YORK, N. Y.

DECORATIVE LIGHTING.

1,314,966.

Specification of Letters Patent. Patented Sept. 2, 1919.

Application filed April 25, 1918. Serial No. 230,702.

To all whom it may concern:

Be it known that I, HOWARD S. McBRIDE, a citizen of the United States, residing at New York, in the county of New York and State of New York, have invented new and useful Improvements in Decorative Lighting, of which the following is a specification.

This invention relates to improvements in decorative lighting and more particularly to the formation of an illuminated patriotic service emblem device adapted for use in connection with motor vehicles.

The present invention is designed for the purpose of providing an illuminated decoration at this point, the lights employed being preferably, although not essentially, given movements in a more or less circular path during travel of the automobile. In addition, the purpose of the invention is to provide a decoration of this type which is simple and efficient in operation, durable in construction, capable of operating under low power conditions, and which can be manufactured at a relatively low cost.

To these and other ends, the nature of which will be readily understood as the invention is hereinafter disclosed, said invention consists in the improved construction and combination of parts hereinafter fully described, illustrated in the accompanying drawings, and more particularly pointed out in the appended claims.

In the accompanying drawings, in which similar reference characters indicate similar parts in each of the views:—

Figure 1 is a perspective view showing one embodiment of the present invention applied to an automobile hood.

Fig. 2 is a central vertical sectional view of the same, parts being omitted.

Fig. 3 is a cross-sectional view.

Fig. 4 is a detail sectional view.

In the drawings, H indicates the hood of an automobile carrying the usual radiator filling tube T and radiator cap C.

The invention as shown is of the type adapted to provide for movement of the lamps, and the device is shown as supported by tube T through the use of a suitable member 10, one end 11 of which is arranged to be detachably secured to tube T, as by a clamping action, another end of member 10 forming the support for the device. However, as presently pointed out, lamp movement may be omitted, if desired.

The embodiment shown employs a me-

tallic casting 12 which is secured, as by threading, to an insulating member 13 secured in member 10, member 12 being adapted to be connected to one side of a battery 60 or other suitable source of electrical supply (not shown) by suitable means, such for instance as a binding post, indicated at 14. Member 12 is of suitable configuration, shown somewhat as in the nature of a hollow casting carrying an annular portion or annulus 12^a of greater diameter than the portion of the casting secured to member 13, the walls of member 12 being more or less flared outwardly in an upward direction. 70

Mounted to project upwardly from member 13 is a stem 15, to the lower end of which is secured connections leading from the opposite side of the battery, it being understood that insulated member 13, serves to 75 insulate stem 15 from member 12, the stem and member also being insulated from supporting member 10 in suitable manner. Stem 15, in its simplest form, is preferably non-rotatable, being provided with an enlargement 15^a on which is loosely supported the lamp-carrier, the latter being in the form of a sheet metal structure comprising a plate 16 having a plurality of depending arms or supports 16^a, these arms projecting 80 down to approximately the plane of the top of annulus 12^a. Plate 16 is of small diameter as compared to ring or annulus 12^a, and hence arms 16^a are located spaced from said ring, these arms or depending supports being more or less rigid in structure. Each arm or depending support preferably carries a lamp-supporting element in the form of a lamp socket 17 and a supporting member 18 secured to the socket and having an 95 arm 18 which is pivotally connected to the depending support 16^a. While I prefer to employ a socket which will permit of ready substitution of one lamp for another, this may be varied as may be the particular form 100 of socket employed, that shown being in the form of a bayonet slot structure.

Various ways of completing the circuit through the lamp may be employed, that shown in the drawings, and more particularly in Fig. 4, being designed to provide an efficient operation and at the same time permit of rotative action presently referred to without excessive wear. This particular arrangement provides for locating an insulating member 19 within and forming part 105 of socket 17, said member 19 carrying a cas-

ing 20 within which is mounted a pin 21 adapted to normally contact with one of the lamp terminals through the action of a spring 22 which is interposed between one 5 end of pin 21 and a ball 23 which projects from the opposite end of casing 20 and is adapted to ride on ring 12^a, the latter being preferably, although not essentially, provided with an annular race 12^b to coöperate with the balls in providing for anti-friction action. Obviously, pin 21, casing 20, ball 23 and spring 22 constitute a yieldable contact normally engaging a lamp terminal and resting on annulus 12^a.

10 15 A lamp is indicated at L.

As shown, a plurality of depending supports 16^a are employed, these being shown as spaced at substantially equal distances, each support carrying its lamp-supporting element, these elements extending practically radially with respect to the axis of stem 15, so that there is provided an arrangement embodying a plurality of lamps in spaced apart relation, each lamp being electrically connected to stem 15 through plate 16 and its depending supports 16^a, supporting arm 18^a and socket 17, the opposite terminal of the lamp being electrically connected to the opposite side of the battery 20 through the yielding contact, casting 12 and its ring 12^a. Hence, as long as either of the balls 23 remains in contact with ring 12^a, the circuit will be complete through the lamp. Since each lamp, however, has its 25 support pivotally mounted, it will be understood that there is more or less flexibility in the connections which will permit the lamp support to swing in a direction of yield in case material jolting of the automobile 30 may take place, thus reducing liability of damage to the lamp filament, the upward swinging movement breaking the circuit. On the return movement, the yielding contact will tend to cushion the jar which 35 might be placed on the element.

40 Stem 15 preferably extends above the top of plate 16, and forms a support for an element of suitable configuration and preferably secured to plate 16, this element being 45 of the type which tends to rotate in the presence of air currents whether produced by travel of the automobile or otherwise. This element, indicated at 25 may be more or less S-shape in plan (Fig. 3) and may 50 have its wings of any desired configuration and ornamentation, that shown in the drawings having one wing representative of the American flag, while the other wing is an imitation of a service flag, thus forming an 55 emblem structure.

60 As will be understood, plate 16 is loosely supported on enlargement 15^a, and in order to retain it in position as well as to permit of sufficient yielding under jolting action, I 65 preferably provide means for yieldably re-

taining it in its normal position, this means being shown as in the form of a spring 26 mounted above emblem 25 and interposed between washers 27 carried at the upper end of the stem, the latter carrying an adjusting 70 nut 28 by means of which the tension of spring 26 can be regulated. This permits spring 26 to operate not only as a means for retaining plate 16 in its normal position, but also to tend to provide a friction 75 factor in connection with the rotation of the emblem, thus reducing the speed of rotation of the latter and hence of plate 16 and the lamps which are rotated thereby.

80 As will be understood, rotation of the emblem will cause the lamps to travel in a circular path, each lamp being included in the electrical circuit between member 12 and stem 15, the particular manner in which the lamps are supported placing them in 85 parallel relation with respect to the circuit, so that more or less flexibility in operation is provided in use.

85 The lamps are preferably of different colors, the three shown in the drawings being indicated as of the colors red, white and blue, thus providing an ornamental effect which is materially increased as they are caused to travel in a circular path, especially 90 when the movement is not too rapid. 95

90 As will be understood, the pivoted lamp carriers are more or less weighted in order to normally retain balls 23 in position to complete the circuit, any suitable means for providing the weight being adapted for use. 100

100 While plate 16 and depending supports 16^a are held under the restraint of spring 27 as to movement on the stem, thus practically fixing the inner ends of arms 18^a, the arms are free to swing on their pivots, being 105 restrained only by the weighted formation, so as to provide for safety against the effect of jars and jolts damaging the lamps.

110 As will be understood, during the period when the automobile is stationary and the velocity of the wind is insufficient to rotate the emblem, the lamps remain lighted but are stationary, thus giving a decorative effect to a standing automobile, and, if desired, I may retain this feature permanently by 115 making plate 16 and the emblem as separate structures, as by locating a washer therebetween, thus permitting the emblem 25 to have its rotative movements without communicating these movements to the lamp 120 structures. In either case, however, it will be readily understood that the structure is of a type which is sufficiently flexible in character as to reduce liability of damage to the lamps to the minimum in the presence of 125 jolts or other actions of the automobile, and at the same time provide for automatic completing of the circuit to a lamp whenever the circuit has been broken through the jolting action; such jolting action may 130

thus tend to increase the decorative effect through the intermittent make and break of the circuit and lighting and darkening of the lamps.

5 As will be readily understood, the structure is of a simple and efficient type, while the lamps are of a size which can be operated from an ordinary battery structure.

As will be understood, the relative location of the emblem and lamp or lamps is such as to expose the emblem in the light-zone of the lamp or lamps. As a result, the lamp may serve as an illuminating means for the emblem, an arrangement particularly adapted for use as an illuminated patriotic service emblem attachment comprising a supporting structure, an electric lamp carried thereby, an emblem supported by the structure, the parts being relatively 20 located to permit exposure of the emblem within the light zone of the lamp.

While I have herein shown and described one or more preferred embodiments of the invention, it will be readily understood that 25 changes and modifications therein may be found desirable or essential in meeting the exigencies of use, and I desire to be understood as reserving the right to make any and all such changes or modifications as may 30 be found desirable or necessary, in so far as the same may fall within the spirit and scope of the invention as expressed in the accompanying claims.

What I claim is:

35 1. In decorative lighting apparatus and in combination, a stem, a lamp carrier mounted on the stem, a plurality of lamps supported by said carrier with each lamp 40 swingingly supported, a member extending within the path of swinging movement of the lamps and adapted to normally maintain the lamps in a predetermined plane, said stem and member being insulated from each other, means for connecting said member and stem to a source of electrical supply, and a support insulated from the stem and member.

2. In decorative lighting apparatus and in combination, a stem, a lamp carrier 50 mounted on the stem, a plurality of lamps supported by said carrier with each lamp swingingly supported, a member extending within the path of swinging movement of the lamps and adapted to normally maintain the lamps in a predetermined plane, said stem and member being insulated from each other, means for connecting said member and stem to a source of electrical supply, a rotatable ornament carried by the 55 stem above the lamp carrier, and a support insulated from the stem and member.

3. In decorative lighting apparatus and in combination, a stem, a lamp carrier mounted on the stem, a plurality of lamps 60 supported by said carrier with each lamp

swingingly supported, a member carrying an annulus within the path of swinging movement of the lamps and adapted to normally maintain the lamps in a predetermined plane, means carried by the stem and 70 connected to the carrier for rotating the latter, a support, means for insulating said stem and member from each other and from the support, and means for connecting the stem and member to a source of electrical 75 supply.

4. In decorative lighting apparatus and in combination, a stem, a lamp carrier mounted on the stem, a plurality of lamps supported by said carrier with each lamp 80 swingingly supported, a member extending within the path of swinging movement of the lamps and adapted to normally maintain the lamps in a predetermined plane, said stem and member being insulated from 85 each other, means for connecting said member and stem to a source of electrical supply, a rotatable element mounted on the stem and connected to said carrier to rotate the latter during element rotation, and a 90 support insulated from the stem and member.

5. In decorative lighting apparatus and in combination, a stem, a lamp carrier supported thereby, a plurality of lamps, a member insulated from the stem and carrying an annulus, means for connecting said stem and member to a source of electrical supply, and means for supporting the lamps individually on the carrier, with each lamp having 100 a contact normally resting on said annulus to complete the lamp circuit, said means permitting free movement of the lamp to break such circuit between contact and annulus.

6. In decorative lighting apparatus and in combination, a stem, a lamp carrier mounted on the stem and comprising a rigid structure having depending elements and a plurality of lamp-carrying arms pivotally 110 connected to said elements to permit swinging movements of the arms, a member extending within the path of swinging movement of said arms and adapted to form a support upon which the lamp arms may rest and to 115 maintain the lamps in a predetermined plane, a support, means for connecting said member and stem to a source of electrical supply, and means for insulating the stem and member from each other and from the 120 support.

7. In decorative lighting apparatus and in combination, a stem, a lamp carrier pivotally mounted on the stem, said carrier comprising a rigid portion and a plurality of 125 pivotally-mounted lamp-carrying elements extending radially with respect to the axis of said stem, a rotatable element mounted on the stem and connected to said carrier and adapted to form means for rotating the lat- 130

ter, a member having an annulus within the path of pivotal movement of said lamp-carrying elements and adapted to form a support upon which an element contact may 5 rest, whereby the lamps will be normally maintained in a substantially predetermined plane, a support, means for connecting a source of electrical supply to said member and said stem, and means for insulating the 10 member and stem from each other and from said support.

8. In decorative lighting apparatus and in combination, a stem, a lamp carrier mounted on the stem and provided with a 15 plurality of swingingly-supported arms, a lamp carried by each arm, a member extending within the path of swinging movement of said arms and adapted to normally maintain the lamps in a predetermined 20 plane, each arm having a yieldable contact structure adapted to rest upon said member and having a contact element engaging a lamp terminal, whereby each arm is free to move to break connection between said yielding contact and the member, the yielding of 25 said contact tending to provide a cushioning action on return movement of the arm, said member and stem being insulated from each other, and means for connecting said 30 stem and member to a source of electrical supply.

9. In decorative lighting apparatus and in combination, a stem, a lamp carrier mounted on the stem, a plurality of lamps 35 supported by said carrier with each lamp swingingly supported, a member carrying an annulus within the path of swinging movement of the lamps and adapted to normally maintain the lamps in a predetermined 40 plane, means carried by the stem and connected to the carrier for rotating the latter, a support, means for insulating said stem and member from each other and from the support, means for connecting the stem and 45 member to a source of electrical supply, and means carried by the stem for providing a friction factor to retard the movement of the rotating means.

10. As a new article of manufacture, an 50 illuminated patriotic service emblem attachment for automobiles comprising a support-

ing structure, an electric lamp carried thereby, an emblem supported by said structure and adapted for exposure in the light-zone of the lamp, said emblem being rotatively 55 movable by and during automobile travel, said lamp being located out of the path of travel of the emblem, means for accommodating the light zone of the lamp to the shifting movements of the emblem to maintain 60 emblem illumination throughout its entire surface and path of travel, and means for attaching the supporting structure to an automobile part.

11. As a new article of manufacture, an 65 illuminated patriotic service emblem attachment for automobiles comprising a supporting structure, a plurality of lamps carried thereby in spaced relation, an emblem supported by the structure and adapted for exposure in the lighting zone of the lamps, said emblem being rotatably movable by 70 and during automobile travel, said lamps being located out of the path of travel of the emblem, means for accommodating the 75 light zone of the lamps to the shifting movements of the emblem to maintain emblem illumination throughout its entire surface and path of travel, and means for attaching the supporting structure to an automobile 80 part.

12. A display emblem adapted for attachment to motor vehicles comprising a staff or stem, an emblem carried thereby, a lamp positioned below the emblem and 85 located to bring the latter within the light-zone of the lamp, said emblem being rotatively movable by and during automobile travel, said lamp being located out of the path of travel of the emblem, means for accommodating the light zone of the lamp to the shifting movements of the emblem, whereby the emblem may be maintained 90 within the light zone, and means for connecting the lamp to a source of electrical supply, 95 said latter means including a member located below the lamp and forming a support therefor.

In testimony whereof I have hereunto set my hand.

HOWARD S. McBRIDE.
